UNITED STATES PATENT OFFICE.

HERMAN B. HOFFMAN, OF NEW YORK, N. Y.

COMBINATION-GARMENT.

1,251,030.

Specification of Letters Patent. Patented Dec. 25, 1917.

Application filed May 26, 1916. Serial No. 99,965.

To all whom it may concern:

Be it known that I, HERMAN B. HOFFMAN, a citizen of the United States, residing at No. 736 East 163rd street, borough of the Bronx, city of New York, county of the Bronx, and State of New York, have invented a new and useful Combination-Garment, of which the following is a specification.

10 My invention relates to an improvement in ladies' undergarments and is accomplished by combining an envelop chemise and petticoat so as to constitute a single garment. This is effected by lengthening the chemise 15 and extending same the ordinary length of a petticoat and by securing to the inside of the chemise near the waist line two depending flaps, one in the front and one in the back of the petticoat, the back flap containing an 20 envelop tab or band which passes between the legs of the wearer and buttons onto the front flap, so that when the said tab is buttoned or otherwise fastened, there is inside the petticoat the lower part of an 25 envelop chemise.

The object and advantage of my invention is to provide an inexpensive and comfortable chemise, petticoat and envelop combined. The comfort is created by eliminating the 30 bulging ordinarily incident to a separate petticoat worn over the ordinary envelop chemise, and it is inexpensive in that a separate petticoat is unnecessary and it may be made of any material, whether muslin, 35 lingerie, cloth, wool or other textile.

I attain my object by the illustrations set forth in the accompanying drawings.

40 Fig. 2 is another front view of the same showing the arrangement of the envelop inserted in the petticoat.

Fig. 3 is a rear view of the combination showing the rear depending flap containing 45 the envelop tab.

Similar letters refer to similar parts throughout the several views.

In Fig. 1 "a" to "g" represents the upper portion of the chemise; "a" to "f" the petticoat; "c" the front depending flap and "b" the rear depending flap; "d" the envelop tab, being part of the rear depending flap; "e" a piece of binding secured to the center of the front depending flap and containing button holes, to which tab or band "d" of the 55 rear depending flap is buttoned or secured, thus forming the envelop; "a" to "a" is a line showing the beginning of the depending flaps "b" and "c" attached thereat, this line being a short distance below the waist portion of the 60 garment. "f" to "g" represents the length of the entire combination, being from the shoulders to the bottom of the garment. "b" and "c" represent the envelop within the 65 petticoat. The flaps "b" and "c" are preferably substantially the width of the garment.

In Fig. 2 "d¹" shows the envelop tab or band extending from the rear depending flap "b". "d" shows the said envelop tab fastened to "e" by buttons, hooks or other 70 means. "f" "f" "f" "f" is the bottom of the front view of the petticoat exposed.

In Fig. 3, which is the rear view of the combination, "d¹" is the said envelop tab extending downward from the rear depending flap. "f" "f" "f" "f" is the bottom of the 75 rear view of the petticoat exposed.

Having thus described my invention, I claim as new and desire to secure by Letters Patent:

1. In a garment, the combination of a chemise having a skirt or petticoat, depending front and back flaps permanently attached to the inside of the skirt of the garment a short distance below the waist portion thereof, a band adapted to be passed between the legs of the wearer to connect the flaps, and fastening means detachably connecting an end of the said band with the free end of a flap, whereby leg or drawer 90 portions are formed wholly within the skirt a considerable distance above the lower edge of the same so that a full skirt or petticoat effect is maintained.

2. A chemise and full-length petticoat 95 united in one garment with inside front and rear flaps substantially the width of the garment depending from near the waistline, and a tab united to one flap substantially centrally thereof and having means 100 for detachably securing it to the other flap.

In testimony whereof I have hereunto set my hand in the presence of two subscribing witnesses.

HERMAN B. HOFFMAN.
